UNITED STATES PATENT OFFICE.

EVERETT B. CUSHMAN, OF LINCOLN, NEBRASKA, ASSIGNOR TO CUSHMAN MOTOR WORKS, OF LINCOLN, NEBRASKA.

SPLASH LUBRICATING SYSTEM.

1,099,916.

Specification of Letters Patent. Patented June 16, 1914.

Application filed September 5, 1912. Serial No. 718,697.

To all whom it may concern:

Be it known that I, EVERETT B. CUSHMAN, a citizen of the United States, residing at Lincoln, in the county of Lancaster and 5 State of Nebraska, have invented a new and useful Splash Lubricating System, of which the following is a specification.

This invention relates to improvements in splash lubricating systems especially de-10 signed for gasoline motors.

One object of the invention is to provide motors with an oiling device operated by the movement of the crank of the engine.

A further object of the invention is to 15 provide an oiling device which is simple and effective and which is adapted to motors of any ordinary type.

In the accompanying drawings, illustrating 20 the preferable embodiment of my invention, wherein it will be understood that various changes and modifications may be made relating to the detailed construction and arrangement of the parts without departing from the spirit thereof: Figure 1 is 25 an elevational view of the entire motor, with a part of the lower plate removed to expose the interior to view. Fig. 2 is a horizontal section on the line 2—2 of Fig. 1, looking in the direction indicated by the arrows.

30 In carrying out the present invention, I provide an ordinary gasoline motor which has the lower part constructed with a casing 1 the sides of which have bearings 3 in which is journaled a shaft 2 provided at its 35 extremity with a fly-wheel 4. The shaft is provided at its middle with a crank 5 engaged by a pitman 6 which is joined to the shaft 2 by means of a journal 7. The lower member of the journal 7 has a nose 7' the 40 lower face of which is inclined, said nose constituting means for engaging the oil contained in the casing 1 and splashing it upwardly in the direction indicated by the arrows in Fig. 1.

45 The oil receiver which is indicated generally as 8 is threaded into or formed integral with the lower portion of the engine casing 1 a little above the shaft 2, as shown in Fig. 1. The extension 9 extends through 50 the wall of the oil receiver of the engine to a sufficient extent to expose the opening at the inner end of the extension and afford a backward track for the oil into the re-

ceiver 8. From the receiver 8 near the bottom extend pipes 10 which project around 55 the lower portion of the motor to the bearings 3 of the main shaft 2. The pipe 10 as well as the lower part of the oil receiver 8 is preferably filled with cotton or other suitable fibrous substance indicated at 11, thus 60 affording a suitable filter for the oil. To afford ready access to the interior of the receiver 8 I provide a threaded plug 12 in the top thereof which can be easily removed whenever necessary. 65

It is to be understood that that portion of the structure constituting the present invention can be applied readily to an engine already in use. This is done by boring a hole in the casing 1 and inserting the tubular nipple or extension 9 and connecting the receiver 8 to the bearings or journals 3 by means of the pipes 10. By then placing a lubricant in the casing 1 and starting the motor it will be seen that, as the crank 70 shaft rotates, the nose 7' will splash the lubricant upwardly as indicated by the arrows. A portion of the lubricant will gravitate into the inlet end of the opening in the extension 9 and will thus flow to the receiver 8 75 where it will be strained through the fibrous filtering material in the casing and will be directed from said casing through the pipes 10 to the bearings. It will be noted that the extension 9 is so shaped as to be extended 80 readily into the casing and that the passage leading through this extension has its inlet formed in the top of said extension so that oil when thrown upwardly is free to gravitate into the inlet end of the passage. 85

It is to be understood that it is not necessary to place the fibrous filtering material in the pipe 10 as, if desired, said material can be located solely in the receiver 8 or, if preferred, solely in the pipe 10. 90

Having thus described my invention what I claim and desire to secure by Letters Patent is:

The combination with a crank shaft, and means for rotating the same, of a casing 100 housing the crank portion of the shaft, means movable with said crank portion for splashing upwardly the lubricant contained in the casing, and a lubricating attachment including a receiver, a nipple extending 105 therefrom and insertible into the wall of

the casing, said nipple having a passage extending therethrough and provided with an inlet in the top of the nipple and within the casing to receive lubricant gravitating after being splashed within the casing, and means for conveying lubricant from the receiver to the bearings of the shaft.

In testimony that I claim the foregoing as my own, I have hereto affixed my signature in the presence of two witnesses.

EVERETT B. CUSHMAN.
